CLAIM

The ornamental design for a mouthpiece for a spirometer, as shown and described.

DESCRIPTION

FIG. 1 is a perspective view of a mouthpiece for a spirometer showing our new design;
FIG. 2 is a front view thereof;
FIG. 3 is a side elevational view thereof, the opposite side elevational view being identical thereto;
FIG. 4 is a back view thereof;
FIG. 5 is a top view thereof; and,
FIG. 6 is a bottom view thereof.

FIG. 1

FIG. 5

FIG. 2

FIG. 3

FIG. 4

FIG. 6
